UNITED STATES PATENT OFFICE.

LUTHER D. SMITH, OF TOLEDO, OHIO.

ELECTRIC HEATING ELEMENT.

1,393,325.

Specification of Letters Patent. Patented Oct. 11, 1921.

Application filed February 24, 1919. Serial No. 278,899.

To all whom it may concern:

Be it known that I, LUTHER D. SMITH, a citizen of the United States, and a resident of Toledo, in the county of Lucas and State 5 of Ohio, have invented certain new and useful Electric Heating Elements; and I do hereby declare the following to be a full, clear, and exact description of the invention, such as will enable others skilled in 10 the art to which it appertains to make and use the same, reference being had to the accompanying drawings, and to the characters of reference marked thereon, which form a part of this specification.

15 This invention relates particularly to electric heating coils of the character in which a current of electricity is passed through a conductor, which offers sufficient resistance to the current to produce a required amount 20 of heat under variable conditions of the electrical voltage, and has for its primary object to render said heating coil or conductor more durable and lasting in use.

It will be understood that the alloys of 25 metal now in common use have various resistance conductivity and that by variations of length and cross section various carrying capacities for creating a desired amount of heat can be obtained, and that alloys such 30 as chromium and nickel are now frequently used in single strands of adequate size and length to obtain desired temperatures when placed in an electric circuit.

It will also be well known that in the 35 preparation and alloying of different metals uneven results are obtained and that when the alloyed resistor is placed in use, sections of the coil will become hard and brittle and "burn-outs" readily occur by a 40 high temperature, such as would be generated in the coil by the passage therethrough of a current of higher voltage than it was designed in cross section or length to carry; the frequency of defects and "burn-outs" 45 depending upon the unequal alloying of the basic materials employed and upon defects in drawing and misuse.

I have discovered that by forming a resistance or heating coil of two or more suitable conductors of either pure or alloyed metal and placing them in intimate contacting relation, as by twisting or interweaving them together with two at least thereof of different physical properties 50 or electrical characteristics, the united

strands or conductors will endure very considerable variations in voltage, and in case one or more strands burned out because of unequal alloying of the metal or by reason of defects therein, the union is 60 maintained by the other member, acting as a truss wire or support to carry the current across the gap.

Obviously there is nothing new in uniting the ends of a broken heating coil by 65 twisting another wire of the same or different electrical properties around each end for the purpose of closing the circuit. This is common practice arising from the frequency with which alloyed metals burn out 70 under electrical resistance heat. So far as I know, however, no interwoven or twisted plurality of strands of unlike electrical properties have been employed as a resistance element or heating unit and no auxiliary strand of suitable material has been united with the prime electrical resistance 75 wire or wires to serve as a continuous truss wire therefor and to form a bridging union where breaks or burn-outs occur therein. 80

The object of my invention is to produce a heating coil in which these defects shall be overcome in a simple and convenient manner, and while I would not limit myself to the use of any of the common alloys 85 or pure metals now employed, I will, for example, instance the use of 25 feet of #25 gage alloy metal of chromium and nickel in an electric circuit of 110 volts, giving a dissipation of approximately 200 watts and 90 heat sufficient to turn the metal slightly red. If this wire is shortened, as commonly done, to 7 feet in length, it will give approximately 700 watts dissipation and become white hot to a melting point and will last 95 but a very short time in use. I find, however, that by twisting or otherwise intimately uniting with the 25 foot length of resistance wire, a wire of different physical properties, as for instance the metal known 100 as monel, and preferably connecting the interwoven or intimately connected wires in parallel relation in an electric circuit, the coil will dissipate 700 watts and stand the strain of heat without deterioration or 105 "burn-outs", even at double the voltage, and that when "burn-outs" occur, they occur in the alloyed material and not in the truss strand.

In the drawings I have illustrated a three 110

strand resistant coil. While each strand preferably has different physical properties or electrical resistance, two may be of like character if desired, and each of said strands 5 may be of pure or alloyed metal. Various metals suitable for the purpose can be used. Very satisfactory results are obtained by the use of one strand of alloyed chromium and nickel and another strand of monel metal.

Having thus described my invention, what I claim as new and desire to secure by Letters Patent, is—

1. An electric resistance heating element 15 composed of a plurality of conductors, combined side by side in intimate contact and having different physical properties.
2. An electric resistance heating element composed of a plurality of electrical conductors twisted together in intimate relation 20 and having different electrical conductivity.
3. An electric resistance heating element composed of a plurality of electrical conductors, with one of suitably alloyed material 25 of chromium and nickel, supported and in-

timately interwoven with one of monel metal.

4. An electric resistance heating element composed of a plurality of electrical conductors, with one of suitable alloyed metal 30 supported and intimately interwoven with one of lower electrical resistance.

5. A device in which electrical energy is converted into heat, comprising metal conductors intimately connected throughout 35 their effective lengths and having unequal temperature coefficients.

6. An electric resistance heating element composed of a plurality of electrical conductors combined side-by-side in intimate 40 contact, and two at least thereof having different electrical resistance.

7. An electric resistance heating element composed of twisted conductor strands, two at least of which are of different electrical 45 resistance.

In testimony whereof I have hereunto signed my name to this specification.

LUTHER D. SMITH.
